UNITED STATES PATENT OFFICE.

ARTHUR F. POOLE, OF CHICAGO, ILLINOIS.

ELECTRIC-CLOCK SYSTEM.

1,310,373.

Specification of Letters Patent. Patented July 15, 1919.

Application filed February 15, 1915. Serial No. 8,196.

To all whom it may concern:

Be it known that I, ARTHUR F. POOLE, a citizen of the United States, residing at Chicago, in the county of Cook and State of Illinois, have invented certain new and useful Improvements in Electric-Clock Systems, of which the following is a specification.

My invention is an electric clock system, particularly the master mechanism therefor, and is an improvement on certain features of the electric clock system described in my co-pending application Serial No. 861,360, filed September 12, 1914. In the said application I have described a system of electric clocks suitable for use in connection with an electric light and power installation. The secondary clocks consist of synchronous motors connected to the conductors used for the distribution of light and power, and the alternating-current generator at the central station is synchronized with a master clock, whereby these secondary clocks will reproduce the time of the master clock. In said application, the master clock which serves to synchronize the generator is shown mechanically connected thereto. This arrangement necessitates the master clock being located at the central station.

My present invention has for its object the provision of means whereby the master clock will be located at any convenient locality, not necessarily at the central station, and the connection between the master clock and the alternating-current generator whereby the latter is synchronized is a purely electrical connection. My improved arrangement which forms the subject of my present invention thus has the advantage that an ordinary clock may be used as the master clock and that this clock may be located away from the central station in a place not subject to the jar and vibration necessarily present in a central station, thus enabling the master clock to keep much more accurate time than otherwise.

My present invention may be best understood by reference to the accompanying sheet of drawings, in which,

Figure 1 is a diagrammatic arrangement of the parts necessary to accomplish the results as above set forth; and

Fig. 2 is a detail showing the connection of the worm wheel controlling the throttle, 55 with the rod on which it is mounted.

Reference thereto will disclose at 1 a master clock, which may be of any suitable construction, and is provided with a contact to close an electric circuit periodically, which 60 period, for the purposes of this present invention, may be taken as one second. Since clocks provided with mechanism of this kind are old in the art, it is not necessary to enter into a detailed description of the same. 65

The master clock 1 is connected by wires 2 and 3 to a relay 4, and through a pair of contacts 5 and 6 to a battery 7, which has one side connected to the ground 9. The relay 4 is provided with an armature 10, 70 which is normally held against its back stop 11 by a retractile spring 12, and which when attracted by the relay 4 serves to contact with points 13 and 14. It must be borne in mind that the conductors 2 and 3 are connected to the contact in the master clock, which contact serves to close the circuit once every second. Therefore at every second, upon the closing of the circuit by the master clock, the armature 10 will be attracted by the relay 4 and contact with the points 13 and 14. The contact 14 serves to lock the relay 4 when its armature is attracted, for when the armature 10 is drawn up, a circuit may be traced from the live 85 pole of the battery 7 through the contacts 5 and 6 to the armature 10, to the contact 14, through the relay 4 to the ground 9. Therefore once each second this armature 10 will be drawn up, and remain up, even if the 90 contacts in the master clock 1 are opened, until the contacts 5 and 6 are separated by means afterward to be described. Separation of these contacts 5 and 6 will of course open the circuit from the battery 7, and the armature 10 will thereupon be drawn against its back stop 11. From the contact 13 a circuit may be traced through the relay 15 to the ground 9. This relay 15 is provided with an armature 16 which normally 100 rests against a contact 17. The fact of the armature 10 being drawn up as previously described will cause the armature 16 of the relay 15 to move away from the contact 17, and the circuit controlled by the armature 105 16 and contact 17 will remain open as long

as the armature 10 of the relay 4 is maintained in its front position.

18 is a diagrammatic representation of a shunt motor which is driven from the 5 mains 19 and 20. It is provided with a field coil 21 and an auxiliary resistance 22 in series with said field coil. This 10 motor 18 is geared by a worm 23 to a worm wheel 24 on a shaft 25, rigidly attached to which is an arm 26 which serves to open the contacts 5 and 6 at each revolution of the shaft 25. The worm 23 and wheel 24 are 15 so proportioned that the shaft 25 revolves synchronously with the closing of the circuit by the master clock 1,—that is, in the present instance, the shaft 25 makes one revolution per second. The motor 18 is so arranged that when running under the influence of the field coil 21 it runs somewhat slower 20 than the normal rate; but when running under the influence of the field coil 21 with the auxiliary resistance 22 in series therewith, it runs somewhat faster than the normal rate. It will be observed that the auxiliary 25 resistance 22 is normally shunted by the armature 16 being in contact with the point 17. Therefore as the armature 16 is periodically attracted by the current from the master clock, as just described, it is obvious 30 that the motor 18 will run faster than the normal speed corresponding to the armature 16 being away from the contact 17, and slower than the normal speed corresponding to the armature 16 being in contact with 35 the contact point 17.

It will be remembered that the master clock closes the circuit 2, 3 once each second, and that in consequence thereof the relay 15 attracts its armature 16 once each second; also that when this armature 16 has been once attracted it will remain attracted until the arm 26 has separated the contacts 5 and 6. Now assume that in the normal running of the apparatus, just at the instant 40 when the master clock closes the circuit, the arm 26 is in the position shown by the dotted line 27. The motor 18 will then be accelerated until the arm 26 breaks the contacts 5 and 6. From then on until the next ensuing current from the master clock 45 the motor 18 will be retarded, and when the arm 26 reaches the dotted line 27 again, the motor will be again accelerated. Assume that for any reason the motor 18 is retarded. Then when the master clock 1 closes the circuit, the arm 26 will not have reached the position of the dotted line 27. Consequently 50 the accelerated period of the motor 18 will last longer than normal. Therefore the average speed of the motor will be increased. To take the other case, assume that, after the breaking of the contacts 5 and 6, the arm 26 has reached a position ahead of the dotted line 27 when the master clock 1 55 next closes the circuit. Since the accelerated

period of the motor 18 does not commence until the relay 15 has pulled up its armature 16, it is obvious that in this case the accelerated period of the motor 18 will be shortened and the retarded period of the 70 motor 18 will be lengthened; hence the average speed of the motor will be slower.

As above described, the very fact of the average speed of the motor varying from normal will throw into operation circuit 75 connections which tend to bring said speed back to normal again. It is obvious that the average speed of the shaft 25 will be exactly one revolution per second, or, in other words, it will run in absolute synchronism 80 with the master clock.

I shall now describe the means by which the generator is kept in synchronism with the shaft 25. Rigid to the shaft 25 is a bevel gear 28 which forms one side of a 85 differential gear. The other side of this differential gear consists of a bevel gear 29, which is geared to a synchronous motor 30 in such a ratio that when the alternating-current generator 31 of the central station 90 is running at its normal speed the bevel gear 29 will make exactly the same number of revolutions as the bevel gear 28, except that it will make these revolutions in the reverse direction. The generator 31 is connected to the bus bars 39 and 40, and these are connected to the synchronous motor 30, as shown. Mounted between the bevel gears 28 and 29 is a bevel gear 32 mounted in a gear 33, the system of gears 28, 29, 32 and 100 33 forming an ordinary differential gear. Obviously, if the speed of the generator 31, and consequently that of the synchronous motor 30 running in step therewith, should vary from the normal speed, the bevel gear 105 32 and the gear 33 in which the same is mounted will be displaced in one direction or the other. Meshing in the gear 33 is a gear 34 rigidly mounted on a shaft 35, on which is a worm 36 meshing in a wheel 37 110 which is loosely mounted on the throttle shaft 41. A detail of this mounting is shown in Fig. 2, from which it will be seen that the wheel 37 has in it a stop 43 which plays between the ends of a slot 44 in a cam 45 115 rigidly mounted on the throttle shaft 41; the object of this arrangement being to produce some lost motion between the wheel 37 and the throttle shaft 41, and thus prevent hunting of the engine 38 while the same 120 is being governed. The throttle 46 controls the admission of steam to the prime mover 38, which is belted to the alternating-current generator 31. The worm 36 is so geared to the wheel 37 that in case the generator 125 31 runs faster than the normal speed, as determined by the shaft 25, the gear 34 will be rotated in a direction to shut off the steam, thereby reducing the speed of the engine 38. In case the generator 31 runs 130

slower than the normal speed, consequent 5 rotation of the gear 33, and with said gear the gears 34 and 36, will be in a direction to admit more steam to the engine 38, and thereby increase its speed.

The general plan of my present invention will be recognized as substantially that of the synchronizing apparatus for the generator shown in my co-pending application 10 above referred to; the advantage of my present invention over the arrangement shown in my co-pending application being in the nature of permitting the master clock to be located at some suitable place not necessarily at the central station.

It is obvious that occasional failure of the master clock 1 to close the circuit will not interfere with the correct operation of my invention, since it is not necessary that the 20 shaft 25 be corrected at every revolution. Correction may be omitted for three or four revolutions, or possibly longer, without said shaft getting out of cycle. Attention is also directed to the fact that the ordinary signals 25 as sent out by an observatory may be used to synchronize the generator 31, since, as above described, all that is necessary to synchronize this generator is a source of currents sent into the relay 4 at the rate of one 30 per second. Therefore the master clock 1 may be dispensed with, and the ordinary time signals as sent out from an observatory may be used in place thereof.

Many modifications may be made in the 35 precise arrangement of my invention as herein disclosed without departing from the spirit thereof, since I claim:

1. In an electric-clock system: a master 40 clock; an alternating-current generator; means to send a series of currents periodically, said means being governed by said master clock; and means to synchronize said generator with said periodic currents.

2. In an electric-clock system: a master 45 clock; a relay closed periodically thereby; a generator; and means to synchronize said generator with the periodic operations of said relay.

3. In an electric-clock system: a master 50 clock; means for sending out periodic currents, said means being governed by said master clock; an alternating-current generator; and means for so synchronizing the said generator with the said periodic currents 55 that the frequency of the generator will be constant.

4. In an electric clock system, the combination of a master clock, a differential gear, means to control said gear by said master clock, a throttle, means to control said throttle by said differential gear, said means including a lost motion connection between said throttle and said differential gear.

5. The combination of a master clock, a 60 circuit periodically closed thereby, a relay

in this circuit, an alternating-current generator, and means whereby the generator is so controlled by the relay as to be actuated in synchronism with the master clock.

6. In a clock system, the combination with 70 a master clock and an alternating-current generator, of a motor actuated in synchronism with the clock, a second motor actuated in synchronism with the generator, and means connected between the motors for so 75 controlling the generator that its average speed is constant.

7. In combination with a prime mover, a moving member operating at a predetermined speed relatively to the speed of the 80 prime mover, and having a fixed relation thereto, a master clock, a second moving member mechanically independent of the master clock, and constructed and arranged to maintain an unvarying speed relation 85 thereto, and mechanism controlling the speed of said prime mover dependent for its operation upon the relative movement of said moving members to compensate for the revolutions gained or lost by said prime 90 mover due to a variation in speed thereof.

8. In combination with a prime mover, a moving member operating at a predetermined speed relative to the speed of the prime mover and having a fixed relation 95 thereto, a master clock, a second moving member mechanically independent of the master clock and arranged to maintain an unvarying speed relation thereto, said moving members having a predetermined relation 100 to each other so long as said prime mover maintains a normal rate of rotation, and mechanism depending for its operation upon the relation of said moving members to each other, said mechanism operating to 105 vary said prime mover from normal speed whenever the average rate of rotation of the prime mover does not equal its normal rate of rotation, and continuing to vary the prime mover in speed until its average rate 110 of rotation corresponds to its normal rate of rotation.

9. In combination, a master clock, a prime mover operating at a fixed relation to the 115 said master clock so long as it maintains its normal speed, a moving member mechanically independent of and having an unalterable fixed speed relation to said master clock, a second moving member having an unalterable fixed relation to said prime 120 mover and having a predetermined relation to said first member so long as said prime mover maintains its normal speed, and a differential gear mechanism for influencing the speed of said prime mover whenever the 125 relation between said moving members varies, and for continuing to influence the speed of said prime mover until the predetermined relation between said prime 130 mover and said master clock is restored.

10. In combination, a master clock, a prime mover, means mechanically independent of the prime mover to integrate the revolutions of said prime mover and means 5 mechanically independent of said master clock to synchronize said integrated revolutions with said master clock whereby the total revolutions of said prime mover in a given time, may be held to a predetermined 10 amount and thus maintain the average rate of revolution of said prime mover a constant.
11. In combination, a master clock, an electric generator, means to integrate the revolutions of said generator and means 15 mechanically independent of said clock to synchronize said integrated revolutions with said master clock whereby the total revolutions of said electric generator in a given time, may be held to a predetermined amount 20 and thus maintain the average rate of revolution of said electric generator a constant.
12. In combination, a master clock, a generator of alternating electric current, means to integrate the revolutions of said generator 25 and means electrically connected only to said clock to synchronize said integrated revolutions with said master clock whereby the total revolutions of said generator electric current in a given time, may be held to a predetermined amount and thus maintain 30 the average rate of revolution of said generator a constant.
13. In combination, a master clock, a relay controlled thereby, an electric motor, a resistance in said motor circuit and means controlled by said relay to periodically shunt 35 said resistance in synchronism with said master clock.
14. In combination, a master clock, a relay 40 actuated in synchronism therewith, an electric motor, a resistance in the field of said electric motor and circuit connections to shunt said resistance in synchronism with the actuation of said relay.
15. The combination with, a master clock, 45 an electric motor, means to maintain said motor in synchronism with said clock, and an electric generator, of a second motor actuated in synchronism with said generator, a differential gear mechanism disposed between the motors, a prime mover and means whereby the differential member of the gear mechanism controls the source of power 50 from the prime mover.
16. In a clock system, the combination 55 with a master clock, and an alternating-current generator, of means whereby the clock sends out periodic impulses, and means whereby the periodic impulses cause the generator to develop a frequency that is in 60 synchronism with the clock.
17. In combination, a master clock, an electric motor, means to maintain said electric motor in synchronism with said master clock, a differential gear, one element of 65 which is connected to said electric motor, an electric generator, means to rotate a second element of said differential gear in synchronism with said electric generator, a prime mover and means to control the source 70 of power for said prime mover, said means being connected to the third element of said differential gear.
18. In an electric clock system, the combination of a master clock, an alternating current generator, light and power conductors leading from said generator to a series 75 of lamps and motors supplied with current over said conductors, a prime mover to drive said alternating current generator, 80 means to send out a series of currents periodically, said means being governed by said master clock, and means to synchronize said generator with said periodic currents.
19. In an electric clock system, a master 85 clock, a relay closed periodically thereby, an alternating current generator, electric conductors for the purpose of conducting current generated by said generator to a series 90 of electric lamps and electric motors, and means to synchronize said generators with the periodic operations of said relay, whereby the average number of alternations sent out by said generator in a given period 95 of time may be accurately regulated.
20. In a clock system, the combination with a master clock and an alternating-current generator, of a motor actuated in synchronism with the clock, a second motor 100 actuated in synchronism with the generator, and differential means connected between the motors for so controlling the generator that its average frequency is constant.
21. In a clock system, the combination with a master clock and an alternating-current generator, of a motor actuated in synchronism with the clock, a second motor 105 actuated in synchronism with the generator, and differential means connected between the motors for so controlling the generator that it maintains an average speed for any given 110 period of time.

In witness whereof I have hereunto signed my name this 13 day of Feb., 1915.

ARTHUR F. POOLE.
